WILLIBALD HAMMER, OF USTER, SWITZERLAND, ASSIGNOR TO FIRM ZELLWEGER
A.-G., USTER, SWITZERLAND.

WARP-HEDDLING MACHINE.

Application filed July 20, 1925, Serial No. 44,874, and in Switzerland July 21, 1924.

The invention relates to a warp heddling machine provided with a pattern mechanism for controlling its operation and with separating devices for the heddles for each harness. With machines of this type it is old to cause each separating device to select one heddle after the other of a row of heddles and to successively bring them into a more suitable position for threading. The separating or selecting of one heddle after the other immediately from the row of heddles essentially limits the working speed of the machine; furthermore extraordinary difficulties present themselves with heddles which easily become entangled, such as steel heddles.

In order to ensure a safe and reliable operation of the machine at an increased working speed and when handling any type of heddles, so that heddle after heddle receives its respective warp thread, according to the present invention every single device for separating the heddles is provided with a feeder adapted to separate the heddles into groups from the respective row of heddles and to transport a separated group of heddles to receiving means. A gripping device supplies one heddle after the other from said means to a second place for successively receiving the heddles of the separating device. The heddle at such second place is presented to the holding members moved towards the heddle for securing the latter in position during the passage of the threading needle. The threaded heddle is pushed aside by supporting means, in which movement the threading needle which is preferably rigidly connected to said supporting means partakes, whereupon the threading needle is then withdrawn and returns into its initial position together with the supporting means.

A constructional example of the subject matter of the present invention is illustrated on the accompanying drawings, in which:

Fig. 1 is a side elevation of the machine the threading device having receded.

Fig. 2 is a front elevation and

Fig. 3 is a rear elevation of parts of the machine.

Fig. 4 is a plan view with parts shown in section along line IV—IV in Fig. 1.

Fig. 5 shows part of the machine with the threading device in its forward position.

Fig. 6 shows partly in section the connection between the pattern mechanism with a device for separating the heddles.

Fig. 7 shows in a plan view a bipartite carriage forming part of the threading device, the two parts of the carriage being coupled to each other.

Fig. 8 is a cross-section of Fig. 7 and

Fig. 9 is a plan view of the carriage with the two parts uncoupled.

Figs. 10, 11 and 12 show the threading device in an elevation view, plan view (with parts shown in section) and in front view respectively.

Figs. 13, 14, 15 and 16 show details thereof.

Fig. 17 is an elevation view of the heddle shown in Fig. 16 in a section through its eyelet.

Figs. 18 and 19 serve to explain a safety device controlled by the threading device.

Figs. 20 and 21 show in an elevation view and in a rear view respectively a device for separating the heddles.

Fig. 22 is a section along line XXII—XXII in Fig. 20.

Fig. 23 is a plan view of the device for separating the heddles.

Fig. 24 is a similar illustration as Fig. 23, some parts being, however, omitted.

Fig. 25 is a horizontal section along line XXV—XXV in Fig. 20.

Figs. 26, 27 and 28 show the parts of the device for separating the heddles in different working positions.

Fig. 29 shows a diagram of the electric connection to the safety device controlled by the threading device.

To the upper support 2 of the machine frame 1 the harnesses 3 (Figs. 1, 2 and 5) are attached by threading the eyelets at the ends of the heddles to bars provided to that end on the support 2; in Fig. 1 six harnesses are shown. On the lower rails of the frame 1 a carriage 4 is guided in the longitudinal direction of the harnesses, on this carriage the pattern mechanism 5, the electric motor

6 and six devices A for separating the heddles are arranged, a device A belonging to each harness 3 or row of heddles. The motor

6 imparts rotation to the shaft 8 through the interposition of a worm gear and a belt drive 7, whereby a crank mechanism 9 causes

the front part 10 of a carriage to reciprocate; the rear part 11 of the carriage being

95

105

110

115

at intervals coupled to the front part 10 as will be fully explained hereinafter. The carriage 10, 11 is guided with its wheels on a track 12 provided on the main carriage 4 of the machine. During every to and fro movement of the front part 10 of the carriage the latter abuts with its axle pin 13 (Figs. 2 and 4) against a lever 14 of a ratchet mechanism 15 and displaces the latter against the action of a spring, so that the worm gear 16 imparts a turning motion to the vertical shaft 17. A pinion 18 is fixed to the lower end of the shaft 17 and cooperates with a toothed rack 19 mounted on the frame of the machine and the intermittent turning motion of the vertical shaft 17 causes a step by step movement of the machine carriage 4 along the harnesses 3 arranged one behind the other according as the hedding work proceeds. Upon the return movement of the carriage 10, 11 the part 11 of the latter knocks against the end lever of a lever gear 20, which is operatively connected to a spring loaded ratchet bar 21. That lever is rocked through such an angle that the ratchet bar 21 cooperating with the pins of a head 22 of the device 5 turns the head 22 through one pitch whereby the pattern mechanism is moved accordingly. The latter is provided with rollers 23 arranged on bars and serves to control levers 24, Fig. 6, and spring actuated pins 25 which are arranged in one row parallel to the movement of the carriage 10, 11. Six levers 24 are provided each of which is connected by a link 26 to a supporting lever 27. On each supporting lever 27 a lifter 28 influenced by a suspension spring rests, the lifter forming part of one of the six devices A for separating the heddles and being in operative connection with a control lever 29. A knife 30 is common to the six lifters 28 and rests with its ends in the two supporting and guiding arms 31. Pins provided in the ends of the knife 30 project beyond the arms 31 and enter slots of levers 32 Fig. 2. The knife is thus reciprocated by the rocking of the levers 32 and the latter are fixed to a shaft 33 common to both and the shaft 33 is in operative connection with a control lever 36 by means of a link and lever 34 and a shaft 35. The control lever 36 receives its movement from a cam disc 37 (Figs. 1-4) fixed to the shaft 8 and is pressed against the lateral face of said cam disc by the action of a tension spring.

When the levers 24 are not influenced by one of the rollers 23 of the pattern device they are in such a position that the lifters 28 resting on the supporting levers 27 and being lowered in comparison to this position shown in Fig. 6 are out of the path of the knife 30. If one of the levers 24 is rocked out of its neutral position by the action of a roller 23 the supporting lever 27

connected to said lever 24 is then so rocked that it lifts the respective lifter 28 into the path of the knife 30. Thereupon this lifter 28 is moved to and fro when the knife 30 is reciprocated as the lifter is engaged by the knife to take part in the forward movement of the latter and is influenced in a corresponding manner by its tension spring during the backward movement of the knife. Thereby the corresponding device A for separating the heddles is rendered operative; the details and the working of the device for separating the heddles will be explained hereinafter.

Upon the turning motion of one of the levers 24 caused by the pattern mechanism the bolt 25 corresponding to the lever is lifted in its guide against the action of the spring in order to uncouple the two parts of the forwardly moving carriage 10, 11. The front part 10 of the carriage is provided on its lower side with a projecting beak 38 (Fig. 9) and an inclined facing 39. When the two parts 10 and 11 of the carriage are coupled together (Fig. 7) the beak 38 of the front part 10 of the carriage is in engagement with a spring loaded coupling hook 42 mounted on the front extension 41 of the rear part 11 of the carriage, while a spring loaded lever 43 mounted on the rear part of the carriage is kept in its inoperative position by a pin 44 provided on the lever and bearing against the inclined facing 39. The lifted pin 25 is situated in the path of the coupling hook 42 which is provided with a lateral arm striking against the pin 25 when the carriage starts to move. Thereby the coupling hook 42 is swung out of engagement with the beak 38 against the influence of the spring and the parts 10 and 11 are uncoupled. Thereupon the rear part 11 of the carriage remains stationary and the front part 10 of the carriage continues its movement caused by the crank gear 9 and returns into its initial position at the end of the stroke. The end face of the extension 41 of the rear part of the carriage abuts now against the bolt 25 causing the turning of the coupling hook 42, and the lever 43, which turns in the inward direction as the front part 10 moves away, embraces the pin 25 and secures the rear part of the carriage in position. When the part 10 moves backward the inclined facing 39 causes the turning motion of the securing lever 43 in the outward direction and the beak 38 acts upon the coupling hook 42 and the two are caused to engage each other. The rear part 11 is thus coupled to the front part 10 of the carriage and both parts return together into their initial position, whereupon both parts move forward together up to the point in which a pin 25 lifted by the pattern device causes the two parts to become uncoupled.

The front part 10 of the carriage is pro-

vided with two parallel bars 45 to one of which a vertical support 46 is attached. A bar 48 is parallel to the support 46 and the distance between bar 48 and support 46 may be adjusted by means of two bolts 47. To the bar 48 two spindles 49, 50 are fixed one above the other, between which a threading needle 51 having a long shaft is located and is also fixed to the bar 48. Between the spindle 50 and the needle 51 a further spindle 52 is arranged and attached to the support 46. A vertical shaft 53 is mounted on the support 46 and is provided at its lower end with an arm 54 which cooperates with two stop pins 55, 56 (Figs. 3 and 4) provided on a rail 57 fixed to the carriage 4. The shaft 53 is further provided with two arms 58, which are operatively connected to the two bolts 47. On the other bar 45 of the front 20 part 10 of the carriage an upright plate 59 is fixed, provided with a switch 60 which is mounted on a screw bolt 61.

To the rear part 11 of the carriage a vertical support 62 is fixed to which a horizontal bar 63 is attached carrying a plate 64 (Figs. 10, 11 and 12). The bar 63 is situated in the vertical plane passing through the threading needle 51 and is provided with a slotted stirrup 65 and with a funnel 66 open at its end for receiving the threading needle 51 and adapted to hold the heddle to its threading position. The funnel 66 is integral with the separating member 67 mounted on a pin 68 provided at the end of the bar 63 and adjacent to an upright plate 69. A plate 70 provided at the front end of the funnel 66 and projecting in the downward direction forms together with an extension 71 at the rear end of the funnel a bearing 40 for the shaft 72. The latter carries a control arm 73 and a pressure arm 74 cooperating with its free end with the mouth of the funnel 66. The shaft 72 is influenced by a tension spring 75 tending to turn it in such a direction that the control arm 73 is held towards the plate 69 for the purpose of cooperating with an inclined facing 77 (Fig. 11) provided on the plate 69. In the front part of the funnel 66 and to both sides of its mouth guide members 77 for the heddle B are arranged, the latter being held by the pressure arm 74 at the front end of the funnel whereupon the threading needle is passed through the eyelet of the heddle.

When the carriage 10, 11 travels forward the above described members forming the threading device and carried by the two parts 10 and 11 of the carriage, which parts are then in the relative position illustrated in Fig. 1, are moved in the direction of the harnesses 3 arranged one behind the other. If, as is assumed in Fig. 5, the foremost harness 3, i. e. the foremost row of heddles has to be dealt with, the foremost pin 25 lifted by the pattern device causes the uncou-

pling of the two parts of the carriage so that the rear part 11 and its accessories are brought to a standstill, the separating member 67 being then situated in the plane of the foremost row of heddles. During the further travel of the front part 10 of the carriage the switch 60 abuts with its inclined front part against a lever 78 carrying a roller and causes a turning of this lever about its fulcrum mounted on the vertical support 62 and against the action of a spring whereby a rod 79 connected to the member 67 is pulled in the downward direction. Thereby the member 67 together with the funnel 66 and the parts connected to the latter are turned about the pin 68 from the lower position shown in Fig. 1 into the upper position illustrated in Figs. 5 and 10 and are held in this position as long as the lever 78 rests on the horizontal portion of the switch 60. During this interval the threading needle 51 moving together with the front part 10 of the carriage, which continues travelling, is projected through the eyelet of a heddle B which has been brought into the position in front of the funnel by the separating device A belonging to the first row of heddles. By the turning movement of the member 67 heddles which happen to be too near to the heddle to be threaded are pushed aside and the funnel 66 is moved into the path of the advancing threading needle 51 and acts as guidance to the latter. During the final stage of the movement of the funnel 66, i. e. when the control arm 73 slides over the inclined face 76, the pressure arm 74 is turned by the action of the tension spring 75 into its operative position (indicated in dash and dot lines in Fig. 16). Thereby the arm 74 urges the eyelet of the heddle B, which is obliquely to the face of the mouth of the funnel 66 to bear against the latter which has been widened to facilitate the turning of the eyelet and to provide for a good seat of the latter in the funnel, whereupon the threading needle 51 is passed through the eyelet and the warp thread or an auxiliary thread to which the warp thread has to be knotted later on in the loom is inserted into the hook of the needle. When the switch 60 advancing further with the front part 10 of the carriage releases the lever 78, the latter is turned by the action of the spring so that it pushes the connecting rod 79 in the upward direction whereby the member 67 and the funnel 66 together with the parts connected to the latter are turned in the downward direction, i. e. are returned into their initial positions. Simultaneously the pressure arm 74 returns into its inoperative position and releases the heddle which has been threaded.

The spindles 49, 50 and 52 are advanced simultaneously with the threading needle 51 in accordance with the movement of the

front part 10 of the carriage. The heddle B through which the threading needle 51 has passed, is situated on the right hand side of the spindles 49, 50 and 52 in Figs. 3 and 12 and to the left in Fig. 2. The spindle 52 serves to keep other heddles situated on the respective separating device away from the heddle to be threaded and the spindles 49 and 50 act as lateral upper and lower supports to the heddle on being threaded. When the front part 10 of the carriage approaches the end of its movement the arm 54 on the vertical shaft 53 impacts against the stop pin 56 provided on the rail 57. Thereby the shaft 53 is turned through a determined angle and the arms 58 cooperating with the bolts 47 move the bar 48 together with the threading needle 51 and the two spindles 49 and 50 towards the support 46 by a corresponding amount. In consequence thereof the heddle which has been threaded is moved in the harness towards the left, when looking at Fig. 2 up to the other previously threaded heddles of this harness.

The front part 10 of the carriage returns thereafter into its initial position, whereby the threading needle 51 is withdrawn from the heddle and pulls the thread inserted in the hook of the needle through the eyelet of the heddle; the switch 60 cooperating with its descending part with the roller of the lever 78 is turned in the upward direction until after the roller has passed below the switch. The plate 64 serves for effecting a lateral displacement of the heddles if a heddle of the hind rows has to be threaded.

The spindles 49, 50 and 52 are returned into their initial positions simultaneously with the threading needle 51. Upon its return movement the front part 10 of the carriage abuts against the rear part 11 and the two parts are automatically coupled together and return together into the initial position; in this manner all the parts carried by the rear part of the carriage return into their initial position in order to be brought forward to operate with the row of heddles selected by the pattern mechanism when the carriage 10, 11 starts its next forward movement. The stroke of the threading needle 51 is sufficiently large to thread heddles of any harness.

Shortly before the carriage 10, 11 reaches its initial position the arm 54 of the vertical shaft 53 strikes the stop 55 on the bar 57. Thereby the shaft 53 is turned back into its initial position so that the bar 48 is moved in the lateral direction and, together with the threading needle 51 and the spindles 49 and 50, takes up its initial position.

To an upwardly extending support 80 on the main carriage 4 a horizontal bar 81 is

fixed, on which a bell-crank lever 82 is mounted. The latter acts as the device for removing the threads from the hook of the threading needle and is held in the position illustrated in Fig. 1 by the aid of a stop pin 83 (Fig. 3) provided on the support 46 when the carriage 10, 11 is in its initial position. When the latter moves forward the bell-crank lever 82 is swung into the position illustrated in Fig. 5 by the action of a spring 84. Upon the return movement of the carriage 10, 11 the bell-crank lever 82 is caused to turn into its first mentioned position by the stop pin 83 whereby a hook 85 provided at the end of the longer arm of the lever 82 catches the warp thread inserted in the hook of the threaded needle 51 and lifts it out of said hook, so that the needle 51 is free for pulling another warp thread through the eyelet of a heddle.

During the above mentioned lateral displacement of the heddle B through the eyelet of which the needle has passed during the forward movement of the carriage 10, 11 the heddle B strikes against a feeler arm 86 (Fig. 18) mounted on the plate 69, and causes a turning of the arm 86 against the action of a tension spring 87. Thereby a rod 88 connected to the feeler arm 86 is so displaced that a contact piece 89 (Fig. 19) arranged on the rod is moved away from a contact piece 90. The two contact pieces 89, 90 are inserted in an electric conductor 91 (Fig. 29), which is connected to a main 92 of the electromotor 6 driving the machine and to a contact lever 93 aside of which a contact lever 94 is provided. With the two contact arms 93, 94 (see also Fig. 1) a contact plate 95 provided on the belt pulley 7 cooperates. If from any reason no heddle is in the position to be threaded, so that the feeler arm 86 is not displaced out of its initial position when the threading needle 51 and the spindles 49 and 50 carry out their movements in the lateral direction subsequent to the movement in the forward direction, the electric connection of the conductor 91 over the contact pieces 89, 90 remains intact. Consequently the contact plate 95 closes an auxiliary circuit in the conductor 91 through the two contact levers 93, 94, in which circuit an electromagnet 96 is arranged, the armature of which is now attracted. Thereby a locking member 97, forming part of a switch and having been up to then secured in position by the armature, is released, so that the switch can be turned by the action of a tension spring 98 and interrupts the motor circuit 92, whereupon the machine stops and can be inspected. When the machine works normally and heddles are presented for threading in the above-described manner, the connection of the conductor 91 over the contact

pieces 93, 94 is interrupted when the contact plate 95 connects the contact arms 93, 94 with each other.

The six devices A for separating the 5 heddles of the six harnesses are mounted in a holder 99 carried by the frame work of the carriage 4. To this end a vertical support 100 is provided with each device A, on which support the control lever 29 is mounted and the tension spring 28 cooperating with the lifter is fixed. At its upper end the support 100 carries a head 101 above which a flat bar 102 (Figs. 20-28) is supported. On the upper side of the latter two 10 locking levers 103 and 104 are mounted which are interconnected by a tension spring 105 and are ordinarily held in their position of rest by said spring. Furthermore a spring 107 is fixed to the bar 102 by means 15 of a set screw 106. On the upper side of the head 101 a slotted lever 109 (Fig. 25) is pivoted about a set screw 108 and is held in its position of rest by a spring 110; in this 20 position an extension 111 on the lever projecting into a slot of the head 101 abuts against the latter. The slotted lever 109 is provided with an upper guide plate 112 and with a roller 113. With the latter a 25 slide 114 cooperates which is guided in a longitudinal slot 115 of the head 101 and is operatively connected to the control lever 29 by means of a pin 116 entering a slot of the lever. A pin 118 projects into a slot 117 of the slide 114, the pin 118 being provided 30 on a sliding piece 119 guided in the slot of the lever 109. Upon the sliding piece 119 a spring loaded lever 120 is mounted which is provided with a beak 121 at its lower side co-operating with the slotted lever 109 and 35 with a switch 122. The switch 122 is mounted in the head 101 by means of a pin 123 and is ordinarily held in its position of rest by means of a spring 124 (Fig. 25), in which position a pin 125 of the switch abuts against the head 101. On the lever 120 the 40 part 126 adapted to supply the heddles is mounted on which a tension spring 120' connected to the lever 120 acts in one direction and a tension spring 127 connected to the lever 127 acts in the other direction. The lever 127 is mounted on the lever 120 by means of a pin 128 which also serves as fulcrum to the part 126 and it is provided with a stop pin 129 for the part 126. Two 45 spring loaded levers 130, 131 are further mounted on the sliding piece 119. The lever 130 acting as feeler is provided with a shorter arm arranged below its longer arm and the shorter arm cooperates with a lever 50 131 acting as gripping device for the heddles the lever 131 being provided with a notch 132 and a stop pin 133.

The separating device for the heddles works as follows:

Let it be assumed that the lifter 28 fol-

lows, by the influence of its tension spring the receding knife 30 (Fig. 6) during the whole movement of the latter, the sliding piece 119 performs then its full stroke through the cooperation of the slide 114. The sliding piece moves thereby from left to right along the slotted lever 109 when looking at the Figs. 20 and 23-28. The beak 121 of the lever 120, which at the beginning rests against the front of the slotted lever 109, pushes during this displacement (forward movement) the sliding piece 119 up the inclined face 122' of the switch 122, which face projects into the path of the sliding piece 119, and is deviated by the switch 80 to the rear of the latter. Thereby the lever 120 is turned such that the gripper 126 gets behind the plane of the row of heddles of the respective harness (this position of the lever 120 is shown in Fig. 27). As soon as the beak 121 of the lever 120 leaves the rear side of the switch 122, owing to a corresponding forward movement of the sliding piece 119, so that the switch does no longer act as an abutment, the lever 120 is turned by the action of the tension spring into its position of rest (Fig. 24) which is determined by a stop pin. Thereby the feeder 126 enters the row of heddles in front of it and separates therefrom a number of heddles B, for instance four heddles (Fig. 23).

The four heddles B, which have been separated by the feeder from the row of heddles are now moved towards the left with regard to Fig. 23, when the sliding piece 119 performs its return movement, which is transmitted by the lifter 28 during the forward movement of the knife 30. Upon the return movement of the sliding piece 119 the beak 121 of the lever 120 turns the switch 122 against the action of the spring 124 in order to be able to pass that part of the switch which projects into the path of the beak 121, the latter abutting then against the front of the slotted lever 109. Thereupon the roller 113 of the slotted lever 109 is reached by the inclined facing 114' of the returning slide 114 and the slotted lever 109 is turned about its fulcrum pin 108 against the action of the spring 110 (this position of the slotted lever 109 being shown in Fig. 26). The feeder 126 moves the four heddles, separated from the other heddles, during the return movement of the sliding piece 119 beyond the locking lever 103, which has been turned correspondingly, into the space present between the flat-iron shaped end part of the spring 107 and the lever 103. During the subsequent forward movement of the sliding piece 119 the slotted lever 109 swings back into its position of rest and the feeler lever 130, arranged on the slotted lever 109 and projecting into the notch 132 of the gripping lever 131, as is shown in Fig. 24, contacts with the fore-

most of the four heddles previously conveyed by the feeder 126 to the space between the spring 107 and the locking lever 103. Thereby the feeler lever 130 is turned 5 against the action of its spring, and recedes from the notch 132 of the gripping lever 131, which in its turn is so turned by its spring that it enters with its prong between the foremost and the following heddle of 10 the supply of the heddles present on the separating device (Fig. 27). The foremost heddle is now caught between the prong of the lever 131 and the feeler lever 130 and in 15 a slot 119' of the sliding piece 119 respectively. This separated single heddle B is moved by the return movement of the sliding piece 119 into the space 134 (Figs. 23 and 28) between the end of the spring 107 and the locking lever 104. In this position 20 the heddle B is presented to the advancing threading device particularly to the guide members 77 in order to be held in position at the funnel after the heddle has been released by the gripping lever 131 of the separating device. This is effected in that during 25 the continued backward movement of the sliding piece 119 the gripping lever 131 abuts by means of its stop pin 133 against the edge 112' of the plate 112 provided on 30 the head 101, thereby the lever 131 is turned to such an extent that its prong is withdrawn from the slot 119' of the sliding piece 119, so that the heddle B does no longer take 35 part in the further displacement movement of the sliding piece 119; during said turning movement of the gripping lever 131, the feeler lever 130 comes again in engagement with the notch 132 so that it is again in the position to start action. During the continued 40 backward movement of the sliding piece 119 the slide 114 with its inclined face 114' reaches the roller 113 of the slotted lever 109 so that the latter is turned as has been explained above. Thereby the sliding piece 119 is moved in an oblique rearward 45 direction out of the plane of the row of heddles, so that the path of movement of the heddle passed through by the threading needle 51 and moved laterally by the spindles 49 and 50 is now unrestricted. During the 50 subsequent forward movement of the sliding piece 119 the gripping lever 131 grips in the manner described above another heddle from the supply of heddles on the separating device between the locking lever 103 and the spring 107. Owing to the abutting of the feeler lever 130 and of the sliding piece 119 respectively against the separated supply of heddles the forwardly moving sliding piece is held up so that the beak 121 of the lever 120 is at first not allowed to move beyond the rear side of the switch 122 and travels therefore the same path as on its forward movement when the sliding piece 119 returns so that the feeder 126 does not

reach the heddles to be separated and to be supplied to the separating device; the lifter 28 does not follow the whole return movement of the knife 30. However before the supply of heddles on the separating device 70 is exhausted, the sliding piece 119 attains its full stroke so that the beak 121 of the lever 120 moves beyond the switch. The above described working is then repeated whereby the feeder 126 supplies heddles from the row 75 of heddles to the separating device, so that a fresh heddle may always be presented to the threading device.

I claim:

1. In a warp heddling machine in combination, means adapted to receive a plurality of harnesses, a threading needle, a device provided for every harness and adapted to separate the heddles in groups from the row of heddles in a harness, means forming 80 part of every such device and adapted to engage the individual heddles of a separated group and to transport a heddle individually to be operated upon by the threading needle, and a pattern mechanism controlling the 85 selective operation of the individual separating devices.

2. In a warp heddling machine in combination, means adapted to receive a plurality of harnesses, a threading needle, a device provided for every harness and adapted to separate the heddles in groups from the row of heddles in a harness and to transport the separated group of heddles, means 90 provided with every separating device and adapted to receive the transported group of heddles, gripping means forming part of every such device and adapted to engage the individual heddles of a separated group and to transport a heddle individually, holding 95 members adapted to engage every individual heddle transported by said gripping means during the passage of the threading needle, and a pattern mechanism selectively controlling the selection of the separating devices. 100

3. In a warp heddling machine in combination, means adapted to receive a plurality of harnesses, a threading needle, a device provided for every harness and adapted to 115 separate the heddles in groups from the row of heddles in a harness and to transport the separated group of heddles, means provided with every separating device and adapted to receive the transported group of heddles, gripping means forming part of every such device and adapted to engage the individual heddles of a separated group and to transport a heddle individually, holding 120 members adapted to engage every individual heddle transported by said gripping means during the passage of the threading needle, abutment means in rigid connection with 125 said threading needle and adapted to displace a heddle in a lateral direction, means 130

to impart a length-wise movement to said threading needle, and a pattern mechanism selectively controlling the operation of the separating devices.

5. 4. In a warp heddling machine in combination, means adapted to receive a plurality of harnesses, a threading needle, a device provided for every harness and adapted to separate the heddles in groups from the 10 row of heddles in a harness and to transport the separated group of heddles, said device comprising a guide lever, a sliding piece on which said guide lever is mounted, means adapted to receive the transported group of 15 heddles and gripping means carried by said sliding piece and adapted to engage the individual heddles of a separated group, holding members adapted to engage every individual heddle transported by said gripping 20 means during the passage of the threading needle, and a pattern mechanism selectively controlling the operation of the separating devices.

5. 5. In a warp heddling machine in combination, means adapted to receive a plurality of harnesses, a threading needle, a device provided for every harness and adapted to separate the heddles in groups from the 30 row of heddles in a harness, and to transport the separated group of heddles, said device comprising a guide lever, a sliding piece on which said guide lever is mounted and having a slot, locking levers adapted to receive the transported group of heddles, a slotted lever in which said sliding piece is mounted, a gripping lever carried by said sliding piece and adapted to engage the individual heddles of a separated group and to transport same from said locking levers into said 35 slot of the sliding pieces, a feeler mounted on said sliding piece and cooperating with the heddle to be transported and causing the release of the heddle from said locking levers, a slide operatively connected to the 40 sliding pieces of all the transporting devices, means to impart a to and fro movement to said slide and thereby to said sliding pieces, holding members adapted to engage every individual heddle transported by said gripping 45 means during the passage of the threading needle, and a pattern mechanism selectively controlling the operation of the separating devices.

5. 6. In a warp heddling machine in combination, means adapted to support a plurality of harnesses one behind the other, a carriage consisting of a front part and a rear part, means to impart a reciprocating movement to the front part of the carriage, means adapted to couple together and uncouple said two parts of the carriage, a threading needle carried by said front part of the carriage, a device provided for every harness and adapted to separate the heddles in groups from the 60 row of heddles in a harness, means pro-

vided with every separating device and adapted to receive the transported group of heddles, gripping means forming part of every separating device and adapted to engage the heddles of a group individually, holding members supported on the rear part of said carriage and adapted to engage every individual heddle transported by said gripping means during the passage of the threading needle, and a pattern mechanism selectively controlling the operation of the separating devices.

7. In a warp heddling machine in combination, means adapted to support a plurality of harnesses one behind the other, a carriage 80 consisting of a front part and a rear part, means to impart a reciprocating movement to the front part of the carriage, means adapted to couple together and to uncouple said two parts of the carriage, a threading needle carried by said front part of the carriage, a device provided for every harness and adapted to separate the heddles in groups from the row of heddles in a harness, means provided with every separating device and adapted to receive the transported group of heddles, gripping means forming part of every separating device and adapted to engage the heddles of a group individually, holding members supported on the rear part of said carriage and adapted to engage every individual heddle transported by said gripping means during the passage of the threading needle, said holding members including a funnel serving to guide the threading needle and an organ adapted to press the separated heddle with its eye to said funnel, and a pattern mechanism selectively controlling the operation of the separating devices.

8. In a warp heddling machine in combination, means adapted to support a plurality of harnesses one behind the other, a carriage consisting of a front part and a rear part, means to impart a reciprocating movement to the front part of the carriage, means adapted to couple together and uncouple said two parts of the carriage, a threading needle carried by said front part of the carriage, a device provided for every harness and adapted to separate the heddles in groups from the row of heddles in a harness, means provided with every separating device and adapted to receive the transported group of heddles, gripping means forming part of every separating device and adapted to engage the heddles of a group individually, holding members supported on the rear part of said carriage and adapted to engage every individual heddle transported by said gripping means during the passage of the threading needle, said holding members including a turnably mounted funnel open at its top and serving to guide the threading needle and an organ adapted to press the separated heddle.

with its eye to said funnel, means to turn said funnel and said pressure organ into their operative positions after the rear part of said carriage has been uncoupled from
 5 the said front part and to turn said funnel and said organ into their inoperative positions for releasing the heddle when the threading needle has passed through the heddle, and a pattern mechanism selectively
 10 controlling the operation of the separating devices.

9. In a warp heddling machine in combination, means adapted to support a plurality of harnesses one behind the other, a carriage
 15 consisting of a front part and a rear part, means to impart a reciprocating movement to the front part of the carriage, a threading needle carried by said front part of the carriage, a device provided for every harness
 20 and adapted to separate the heddles in groups from the row of heddles in a harness, means provided with every separating device and adapted to receive the transported group of heddles, gripping means forming
 25 part of every separating device and adapted to engage the heddles of a group individually, holding members supported on the rear part of said carriage and adapted to engage every individual heddle transported by said
 30 gripping means during the passage of the threading needle, said holding members including a turnably mounted funnel open at its top and serving to guide the threading needle and an organ adapted to press the
 35 separated heddle with its eye to said funnel, means to turn said funnel and said pressure organ into their operative positions after the rear part of said carriage has been uncoupled from said front part and to turn
 40 said funnel and said organ into their inoperative positions for releasing the heddle when the threading needle has passed through the heddle, a member on which said funnel is supported, an electric controlling device co-
 45 operating with the drive of the machine and including a feeler carried by said member, said feeler being displaced by the transporting movement of the single heddle and remains in its operative position when no
 50 heddle is transported to cause the stopping of the machine, and a pattern mechanism selectively controlling the operation of the separating devices.

10. In a warp heddling machine in combination, means to receive a harness, a threading needle, a mechanism to separate and move a group of a plurality of heddles from the remainder of the heddles of the harness, said mechanism including means to individually and successively separate the heddles of the separated group for presentation to the needle.

11. In a warp heddling machine in combination, means to receive and hold a plurality of harnesses, a threading needle,

mechanism for each harness to move a group of a plurality of heddles of a harness, said mechanism including means to individually and successively separate the heddles of a separated group for presentation to the needle, and means to selectively operate the mechanisms of the harness. 70

12. In a warp heddling machine in combination, means to receive a harness, a threading needle, mechanism to separate and move a group of a plurality of heddles from the remainder of the heddles of the harness, said mechanism including means to individually and successively separate heddles of the separated group for presentation to the needle, said mechanism arranged to be controlled by the selected group to prevent its operation of group selection until substantially all of the heddles of the group are threaded. 75 80 85

13. In a warp heddling machine in combination, means to receive and hold a plurality of harnesses, a threading needle, mechanism for each harness to move a group of a plurality of heddles of a harness from the remainder of the heddles of the harness, said mechanism including means to successively separate the heddles of the separated group for presentation to the needle, and each of said mechanisms arranged to be controlled by the heddles of the separated group to prevent its operation of group selection until substantially all of the heddles of the group have been threaded, and selector means to select the mechanisms to be operated with respect to their respective harnesses. 90 95 100

14. In a warp heddling machine in combination, means to receive and hold a plurality of harnesses, a needle, a mechanism for each harness for singly presenting a heddle to the needle for threading, selector means to selectively operate said mechanisms and means operated by the selector means to selectively control the operation of said needle with respect to the selected harness to be operated upon. 105 110

15. In a warp heddling machine in combination; means to receive and hold a plurality of harnesses, a needle, a mechanism for each harness for singly presenting a heddle to a needle for threading, selector means to selectively operate said mechanisms, and means operated from said selector means to selectively control the operation of said needle with respect to the selected harness to be operated upon. 115 120

16. In a warp heddling machine in combination; means to hold a plurality of harnesses arranged substantially parallel, a needle, and needle operating mechanism, a pattern device, a mechanism for each harness for singly presenting a heddle to the needle for threading, and selectively operated from said pattern device, the travel of said needle and needle operating mechanisms controlled 125 130

from said device for operation on the selected harness, and heddle parting means moving in conjunction with the needle to part heddles of the harness in front of the harness selected to be threaded.

17. In a warp heddling machine in combination; harness holding means, a needle and needle mechanism, mechanism to move a group of a plurality of heddles of the harness to one side, including means to singly separate the heddles from the group to present them for threading by the needle, means

moving in advance of the needle to part the heddles of the group from the one to be threaded, a main driving shaft, driving means therefor, a control device for said means having an operating element moved with the needle to one side of the heddle to be threaded and means to laterally move the threaded heddle to operate the control device to control said driving means.

In testimony whereof, I have signed my name to this specification.

WILLIBALD HAMMER.
